UNITED STATES PATENT OFFICE.

GEORGE BENSON BABY, OF ST. CATHARINES, CANADA.

ELECTRIC FUSE.

SPECIFICATION forming part of Letters Patent No. 738,874, dated September 15, 1903.

Application filed May 2, 1903. Serial No. 155,256. (No model.)

To all whom it may concern:

Be it known that I, GEORGE BENSON BABY, a citizen of the Dominion of Canada, residing at the city of St. Catharines, in the county 5 of Lincoln, in the Province of Ontario, Canada, have invented certain new and useful Improvements in Electric Fuses; and I do hereby declare that the following is a full, clear, and exact description of the construction and operation of the same.

Fuses of the class specified are used on switchboards to prevent injury to electric machines from overloads or short circuits, and it will be observed that dynamos used 15 for incandescent lighting maintain a constant pressure. Hence if the outside resistance be reduced to a very low value, as it would be in the case of a short circuit, a large rush of current would be the result. Short circuits 20 may thus cause considerable damage unless the circuit is promptly opened, which is very seldom the case. Therefore a fuse is required that will blow without arcing, and my improvements in fuses are calculated to accomplish that result.

My invention consists, first, of two brass rods, one longer than the other, each provided with a square projection near the outer end and threaded above and below the said 30 projection, the latter made to fit in a corresponding square opening in a disk and cap, preferably of annular form, the outer ends of the said rods made to project a short distance through each head or cap and screwed into a 35 tapering terminal. Each inner end of the said brass rods has a hole drilled therein to receive the ends of a fuse-wire, which is soldered thereto. Second, the said rods and fuse-wire are inclosed in a cylindrical glass 40 case, formed at each end with an outwardly-projecting annular rim, which is made to rest in a corresponding seat of an annular collar, which is screw-threaded on the outside, over which a head or cap is screwed, a rubber 45 washer being interposed at each end between the glass rim and collar and between the rim and metallic disk and between the disk and cap, as will be more fully shown hereinafter. The glass case is partly filled with mineral- 50 seal oil, high enough to cover the lower end

of the upper brass rod. An air-opening is made in the top to allow air to escape, which prevents the breaking of the glass case when the fuse blows.

Reference being made to the accompanying 55 drawings, Figure 1 is an elevation of an electric fuse embodying my invention. Fig. 2 is a cross-section of the same. Fig. 3 is a side elevation of the upper and longest brass rod. Fig. 4 is a top view of the same. Fig. 5 is a 60 perspective view of the upper head or cap detached. Fig. 6 is a plan of the upper copper disk. Fig. 7 is an edge view of the same. Fig. 8 is a plan of the lower rubber washer, showing square central opening. Fig. 9 is 65 an edge view of the same, showing thickness. Fig. 10 is a plan and edge view of the extra rubber washer on the bottom copper disk. Fig. 11 is a cross-section of the upper collar, showing seat for glass cylinder. Fig. 12 is a 70 similar view, but showing the lower collar. Fig. 13 represents an end view of the bottom terminal; a side view of which is shown in Figs. 1 and 2. Fig. 14 is a top view of the upper terminal, a side view of which is shown 75 in Figs. 1 and 2.

Similar letters refer to similar parts throughout the several views.

A represents a brass rod provided near its upper end with a square projection b, as 80 shown at Figs. 2 and 3 and 4. It is also screw-threaded above and below the said projection b. The latter is made to fit in a corresponding square opening c in a circular head O and also in a square opening a in a copper disk F 85 and circular rubber washer d. A metal terminal, as E, Figs. 2 and 14, is screwed on the top projecting end of the said rod A, and the threaded nut D is screwed on the rod under the disk F to hold the aforementioned parts 90 together. The square projection b in the corresponding square openings of the head, disk, and washer prevents the rod from turning when the terminal is screwed on the rod. A', Fig. 2, represents a similar brass rod to the 95 upper one described, only shorter, and also provided with a square projection B', made to enter and to fit into a corresponding square opening c' in the head O', rubber washer d', and copper disk F', with a terminal E' screwed 100

on the outer end of the said rod and a nut D' screwed on the opposite side, with a rubber washer e interposed between the said nut and the copper disk F' to hold the parts tightly together and make them fluid-tight.

The longer upper rod A and the lower and shorter one A' are connected together with a fuse-wire B, which is inserted in drilled holes in the end of each rod and soldered therein.

10 The top and bottom parts are held together by means of a cylinder G, which preferably may be of any transparent substance, as glass, and a seated collar K at the top and K' at the bottom, each of which is provided with an annular seat f, formed on the top and bottom edges, respectively, of the said collars, the said glass cylinder having a flange a at the top and bottom which rests in the said seat of each collar. The said collars (which preferably

15 may be of hard vulcanized fiber or hard rubber) are screw-threaded on the outside, and the collars are made to encircle the glass case, and the top and bottom flanges a of the cylinder G are made to rest in the said seats f of

20 the collars k and k', with a rubber washer g above it and one, h, below it, and the heads O and O', which are threaded on the inside, are screwed on the collars. An air-opening p is made in the top head O, disk, and rubber washer, and a small tube Q, of brass, will

25 be made to pass through the openings and be screwed into the metal disk F. The object of this vent is to allow the air to escape when the fuse blows from any cause which would

30 throw the oil upward and expel the air, preventing the bursting of the glass cylinder. The oil falling back again after the fuse blows extinguishes the arc and prevents the current from arcing, thus preventing injury to the

35 electric machines and switchboards from short circuits or overloads.

It will be observed that the collars K and K' are also provided each with an inner annular projection i around the inside lower edge of the top collar K and a similar annular projection i' around the top inner portion of the lower collar, as shown more fully in Figs. 11 and 12. These annular projections are for the purpose of keeping the collars 40 steady in place on the cylinder.

The top electrical terminal E and the bottom one, E', are each screwed on the respective ends of the brass rods A and A'. The top one, E, is of a slightly-different form to 45 the lower one, having a slot J and a tapering elongation, slightly wedge-shaped, to enter a corresponding socket on the switchboard. This enables the said top terminal to be thrown in and out of electrical connection.

50 The bottom terminal E is of a different form, but has a downward taper to fit in a corresponding socket attached to the switchboard to hold the device in place and still form electrical connection.

55 It may be here stated that when the fuse

blows it is indicated by the oil in the reservoir turning black, which is caused by the blowing of the fuse forming gases in the oil, and must be replaced.

It will be observed that in the practical 70 operation of the above-mentioned improved electric fuse it has been successfully tested on eleven thousand five hundred volts, fifteen amperes.

In assembling the device the collars are 75 first put on the glass cylinder and the cylinder is flanged at each end while the glass is soft.

Having thus described my device and its advantages, what I claim as my invention, 80 and desire to secure by Letters Patent, is—

1. In an electric safety-fuse, two brass rods placed vertically in alinement, the upper one longer than the lower one, both formed with a square or other shaped projection near the outer end of each, and threaded above and below the said projection, the inner ends of the rods made to receive the ends of the fuse-wire, and inclosed in a glass cylinder containing mineral-seal oil or other non-conducting oil, and formed with an outward flange at each end, and two outwardly-threaded annular collars made to surround the cylinder at each end respectively, both having an annular seat to receive the flanges of the cylinder, an annular top and bottom cap made to screw on the said collars respectively, terminals screwed on the outer ends of the said rods which project through the caps, and inside nuts on each rod to hold a washer and metal disk in each cap, substantially as and for the purpose specified.

2. In an electric fuse, two vertical rods, with a fuse-wire connecting each, a square or other shaped projection on the said rods, caps with square central openings to receive the projections on the rods, a glass cylinder containing mineral-seal or other non-conducting oil sufficient to submerge the fuse, a washer placed under and over each flange of the glass cylinder, a metal disk with central square opening placed over the top of the cylinder and a washer placed on the same, a vent-pipe screwed into the said disk and passing out at the top of the upper cap, substantially as specified.

3. An electric fuse consisting of two rods placed vertically in alinement, the upper one longer than the lower one, with a fuse-wire connecting each, inclosed in a glass case, the same containing a mineral-seal or other non-conducting oil, a collar made to surround the said reservoir at each end with seats for the outwardly-turned flanges of the reservoir, a rubber washer placed under each flange, and one above it, a copper disk having a square opening to receive the square projection of the top rod, and an air-gap into which a tube is inserted through a corresponding opening in the top cap, and a nut on the inside screwed

on the top rod to hold the disk and washer above it in firm position, substantially as and for the purpose specified.

4. In an electric safety-fuse the combination of two rods having a fuse-wire connection with each inclosed in a glass case provided with end flanges, and partially filled with mineral-seal or other non-conducting oil, a threaded collar encircling each end of the case, a cap screwed on each collar, an air-

gap pipe in the top cap communicating with the interior of the case, terminals secured to the two rods, all constructed and arranged substantially as and for the purpose specified.

Dated at Hamilton, Ontario, Canada, the 15
25th day of April, 1903.

GEORGE BENSON BÂBY.

In presence of—

JNO. A. BÂBY,

WM. BRUCE.
